(57) **CLAIM**

The ornamental design for a metal sheet material, as shown and described.

DESCRIPTION

FIG. 1 is an enlarged detail of a top view of the metal sheet material shown in FIG. 4;

FIG. 2 is an enlarged detail of a bottom view of the metal sheet material shown in FIG. 5;

FIG. 3 is an enlarged detail of a perspective top view of the metal sheet material shown in FIG. 6;

FIG. 4 is a top view of my design, shown with perspective lines;

FIG. 5 is a bottom view of my design, shown with perspective lines;

FIG. 6 is a perspective top view of my design, shown with perspective lines;

FIG. 7 is a top view according to FIG. 4, shown without perspective lines;

FIG. 8 is a bottom view according to FIG. 5, shown without perspective lines; and,

FIG. 9 is a perspective top view according to FIG. 6, shown without perspective lines.

The evenly-spaced broken lines represent the boundary of the claim and form no part of the claimed design.

The dot-dash-dot lines shown in FIGS. 4–6 represent the boundaries of the details shown in FIGS. 1–3, respectively, and form no part of the claimed design.

The thickness of the metal sheet material forms no part of the claimed design.

The metal sheet material can be used as a covering material for an automobile part, such as e.g., a hood or bonnet, a door, a roof, a floor, a trunk lid, a bumper, a crumple or crush zone (box), a door beam, etc., or as an interior or exterior covering material for building construction materials, such as e.g., a wall, a pipe, etc., or as a covering material for a container configured to hold one or more items, such as e.g., food or medicine. The metal sheet material may comprise iron, aluminum and/or alloys thereof, such as, e.g., steel.
